DESIGN FOR A NOSE PAD FOR SPECTACLE FRAMES

Charles J. Eagle, Rochester, N. Y.

Application September 4, 1934, Serial No. 53,197

Term of patent 3½ years

To all whom it may concern:

Be it known that I, Charles J. Eagle, a citizen of the United States, residing at Rochester, in the county of Monroe and State of New York, have invented a new, original, and ornamental Design for a Nose Pad for Spectacle Frames, of which the following is a specification, reference being had to the accompanying drawing, forming a part thereof.

Figure 1 is a front elevation of the nose pad for spectacle frames, showing my new design.

Figure 2 is a side elevation of the nose pad, showing my new design and looking at it from the right in Figure 1.

Figure 3 is a side elevation of the nose pad showing my new design looking at it from the left in Figure 1.

Figure 4 is a rear elevation of the nose pad showing my new design.

Figure 5 is a horizontal sectional view of my

nose pad showing my new design, the section being taken on the line 5—5 of Figure 4.

Figure 6 is a horizontal sectional view of the nose pad showing my new design, the section being taken on the line 6—6 of Figure 4.

The novel features of my design, as shown in the present embodiment, include a convexed front, a concaved back, a substantially circular upper section terminating into a reduced downwardly and laterally curved lower section, so as to have the convexedly protruding edge of the circular upper section on one side of the pad arranged above the convexed edge of the lower section, with a concaved edge provided between the upper and lower section on the opposite side of the pad.

I claim:

The ornamental design for a nose pad for spectacle frames, as shown and described.

CHARLES J. EAGLE.
